UNITED STATES PATENT OFFICE.

ATHERTON D. CONVERSE, OF WINCHENDON, MASSACHUSETTS.

COLLAPSIBLE SHOO-FLY ROCKER.

1,079,399.

Specification of Letters Patent.

Patented Nov. 25, 1913.

Application filed March 14, 1912. Serial No. 683,873.

To all whom it may concern:

Be it known that I, ATHERTON D. CONVERSE, a citizen of the United States of America, and a resident of Winchendon, in the county of Worcester and State of Massachusetts, have invented certain new and useful Improvements in Collapsible Shoo-Fly Rockers, of which the following is a specification.

10 This invention relates to collapsible rockers, and particularly to that class of rockers which are known to the trade as "shoo-fly" rockers.

15 The object of the present invention is to provide a rocker which will be collapsible and occupy very little space in transit and in storage, and which will be very rigid when put into operative condition.

20 The present invention consists primarily in providing a collapsible rocker consisting in part of a folding seat the opposite edges of which are hinged or otherwise pivotally secured to the side frames, said seat being adapted to fold upwardly to permit the side frames to be moved toward each other when the rocker is to be shipped or stored, and in providing the rocker with a folding back the opposite edges of which are hinged or pivotally secured to the side 25 frames in such position that when the back is extended the lower edge thereof will extend partially over the upper face of the seat portion and retain said seat portion in extended position. This back portion is adapted to fold rearwardly when not in use and the lower corners of its front face are chamfered off to permit the simultaneous folding of the back and seat portions.

25 The invention further consists in providing said folding seat and back with a folding cushion of peculiar construction, together with means for retaining said cushion on said back and seat portions when the rocker is in use.

40 The invention further consists in certain novel features of construction and arrangement of parts which will be fully understood by reference to the description of the drawings and to the claims hereinafter given.

45 Of the drawings: Figure 1 represents a plan of a rocker embodying the features of the present invention, said rocker being shown in condition for use. Fig. 2 represents a similar view of the same, showing the rocker collapsed and in condition for storage or shipping. Fig. 3 represents an

50 elevation of the collapsed rocker. Fig. 4 represents a transverse section, the cutting plane being on line 4—4 on Fig. 1. Fig. 5 represents an enlarged section through the seat and back, the cutting plane being on line 5—5 on Fig. 1. Fig. 6 represents a rear view of the removable cushion. Fig. 7 represents a plan view of the same, and Figs. 8 and 9 represent respectively an elevation and edge view of a portion of one part of the folding back showing the chamfered lower corner thereof.

55 Similar characters designate like parts throughout the several figures of the drawings.

In the drawings, 10 represents a side frame which may be of any desired shape, as for instance, the shape of a horse or other animal, as indicated in Fig. 3 of the drawings. The frame 10 is composed in part of a curved rocker member 11 adapted to rest upon the floor and rock in the usual manner. Interposed between the side frames 10 is a folding seat 12 centrally divided at 13, the two portions of said seat being connected together by a long hinge 14 extending from one edge thereof to the other. This hinge is secured to the two parts of the seat portion 12 so that said seat portion may be folded upwardly about the pivot of said hinge as shown in Figs. 2 and 3 of the drawings. The opposite edges of said seat are pivotally connected to the side frames 10 by means of hinges 15 secured to the upper face of the seat 12 and the inner face of the side frames as clearly indicated in the drawings. The seat 12 is also provided with a back 18 centrally divided at 19, said back being wholly disconnected from the seat portion 12. The two parts of the back 18 are pivotally secured together by means of a long hinge 20 extending from the top to the bottom thereof and secured to its front face so that said back is adapted to fold rearwardly into the position shown in Figs. 2 and 3 of the drawings. The opposite edges of the back 18 are pivotally secured by hinges 21 or other means to the side frames 10. Pivotally secured to the rear of one part of the back 18 is a latch member 22 adapted to engage a projection 23 secured to the rear face of the other part of said back, this latch 22 and projection 23 coacting to prevent the folding of the back when the rocker is in use.

55 It is obvious that when any weight, as for instance, that of a child, is resting upon the

seat 12, the folding of the seat will be effectually prevented. As an additional safeguard to prevent the accidental folding of the seat portion 12, the lower edge of the back 18 extends over the upper face of said seat 12 adjacent to its rear edge, and thereby firmly locks said seat portion 12 in extended position and effectually prevents any upward movement thereof. When the seat 12 and back 18 are thus extended, and the back 18 is locked by the latch 22, the rocker is sufficiently rigid to support any ordinary weight.

When it is desired to ship the rocker or store it temporarily, the latch 22 is moved about its pivot to disengage it from the hook projection 23, and the back 18 may then be folded rearwardly about the pivot of the hinge 20 into the position shown in Figs. 2 and 3 of the drawings. Simultaneously with the folding of the back 18 the seat 12 is folded upwardly about the pivot of the hinge 14 into the position shown in Figs. 2 and 3, thus permitting the side frames to be moved toward each other as indicated in the drawings. The lower front corners of each part of the back 18 are chamfered off as indicated at 24 in order to permit the simultaneous folding of the seat 12 and back 18, this chamfer being sufficient to keep the two parts clear from contact with each other during the folding operation. This positioning of the back 18 partially over the rear edge of the seat portion 12 so as to prevent its accidental folding when the rocker is in use and giving it an increased rigidity thereby is one of the principal features of the present invention. This feature of the rocker is of great importance as it gives a rigidity to a collapsible rocker which is not found in any rockers of this class now in use. The front of the back portion 18 is provided with a plurality of hooks 25 with which engage the eyes 26 secured to a cushion 27 adapted to be folded on the line 28 as indicated in Figs. 6 and 7 of the drawings. This cushion has riveted thereto projecting members 29 adapted to be inserted in perforations 30 in the seat 12 to retain said cushion in position when in use to prevent its sliding forward during the rocking movement. The cushion protects the user from contact with the hinges on the back and seat of the rocker making it possible by the use thereof to secure the hinges direct to the face of said back and seat where otherwise in order to provide a smooth surface the hinges would have to be inserted into depressions formed therein.

When the rocker is knocked down or collapsed, it occupies but very little space, which is of great advantage in shipping

and also in storage in the factories and wholesale houses.

The device is of further advantage even after being sold, as in the home itself it is often desired to store the rockers temporarily and by folding the device as indicated in the drawings and described herein it may be placed in a closet or other limited compartment and occupy a very little space.

Another advantage of the device is that all of the parts are permanently secured together, so that when the device is opened up for use no part can be missing and prevent its being placed in operative condition. Heretofore knock-down rockers have been used to reduce the cost of shipping and the expense of storage, but when it is necessary to put the rocker on sale and exhibit the same, considerable work has to be performed to place it in operation, and often-times some of the disconnected parts are found to be missing, which makes the use of these knock-down rockers objectionable. In applicant's construction all of these objections have been fully overcome.

It is believed that the operation and many advantages of the invention will be fully understood from the foregoing.

Having thus described my invention, I claim:

1. In a device of the class described, the combination of two side members; a divided seat hinged together and to said side members at its ends and adapted to collapse upwardly to permit said members to be moved toward each other; and a divided back hinged together and at its ends to said side members so as to collapse rearwardly and normally extending over said divided seat retaining it in its normal extended position.

2. In a device of the class described, the combination of two side members; a divided seat hinged together and to said side members at its ends and adapted to collapse upwardly to permit said members to be moved toward each other; a divided back hinged together and at its ends to said side members so as to collapse rearwardly and normally extending over said divided seat retaining it in its normal extended position, said divided back having the lower front corners of each of its vertical ends chamfered off to permit the upward collapse of the divided seat as soon as the divided back commences to collapse rearwardly.

Signed by me at Winchendon, Massachusetts this eleventh day of March, 1912.

ATHERTON D. CONVERSE.
